(57) **CLAIM**

The ornamental design for a basketball aim game, as shown and described.

DESCRIPTION

FIG. 1 is a perspective view of a basketball aim game incorporating my new design;

FIG. 2 is a front elevation view thereof;

FIG. 3 is a rear elevation view thereof;

FIG. 4 is a top plan view thereof;

FIG. 5 is a left side view thereof;

FIG. 6 is a right side view thereof; and,

FIG. 7 is a bottom plan view thereof.

The broken lines for illustrative purpose only and form no part of the claimed design.
